United States Patent Office

Des. 228,269
Patented Sept. 4, 1973

228,269

WATER BED FRAME

David L. Berkel, 1540 Post Road, Stamford, Conn.

Filed Mar. 10, 1972, Ser. No. 233,864

Term of patent 14 years

Int. Cl. D6—01

U.S. Cl. D6—84

Fig. 1.

Fig. 2.

Fig. 3.

Fig. 4.

Fig. 5.

FIG. 1 is a perspective view of a water bed frame showing my new design;

FIG. 2 is an end elevational view;

FIG. 3 is a top plan view;

FIG. 4 is a side elevational view; and

FIG. 5 is a bottom plan view thereof.

I claim:

The ornamental design for a water bed frame, substantially as shown.
